UNITED STATES PATENT OFFICE.

ADOLF HUNZIKER AND SAM HIRSCH, OF BROOKLYN, NEW YORK, ASSIGNEES TO
DUBIED MACHINERY COMPANY, A CORPORATION OF NEW YORK.

JACQUARD-CONTROLLED YARN CARRIER FOR KNITTING MACHINES.

Application filed January 18, 1925. Serial No. 2,826.

To all whom it may concern:

Be it known that we, ADOLF HUNZIKER and SAM HIRSCH, citizens of Switzerland and the United States, respectively, residing 5 at Brooklyn, in the county of Kings and State of New York, have invented certain new and useful Improvements in Jacquard-Controlled Yarn Carriers for Knitting Machines, of which the following is a specification.

The present invention relates to knitting machines and has for its main object to provide means for feeding differently colored yarn threads to produce knitted fabric with 15 variegated designs or patterns.

Another object is to simplify the hitherto used yarn carrier controlling means automatically controlling a reversible yarn carrier having a plurality of thread guides 20 directly from a jacquard card.

A further object of this invention is to so construct the attachment that it can be easily applied to an existing knitting machine.

With these and other objects in view, this invention substantially consists in the construction, combination and arrangement of parts as will be hereinafter fully described and defined in the appended claims.

In the accompanying drawings, Fig. 1 is a vertical section of a knitting machine of well-known construction equipped with the attachment constituting the present invention; Fig. 2 is an end view of a safety locking mechanism for the jacquard card feeding shaft; Fig. 3 is a rear elevation of the yarn carrier seen in the direction of the arrows at 3—3 in Fig. 1; Fig. 4 is a vertical section on line 4—4 of Fig. 1; Fig. 5 is a 30 plan view of the jacquard card and Fig. 6 is an elevation on line 6—6 of Fig. 1.

In the drawing, *b*, *b* denote the two oppositely located oblique needle beds, *n* the needles, *c* denotes the carriage, *s* the main shaft, *r* the rack shaft, *f* the front stationary rod of the main frame and *g* one of the main guide bars of the machine.

Fixed to the carriage, is an upright frame 50, which is provided with a forwardly projecting arm-shaped extension 10' fixed at 10° to a slide 11 mounted on the main guide bar *g* of the machine. The slide 11 is formed with a horizontal extension 11' in form of a flat bar provided at its end with 55 a ring-shaped portion 11'' slidably mounted

on the front stationary guide rod *f* of the frame. The frame 10 is formed with two vertically superposed bearings 10³, 10⁴ in which is rotatively mounted a vertical spindle 12 disposed centrally between the needle beds *b*, *b*. The lower end of said spindle is provided with a member 13 formed with two oppositely located guide openings 13' for two different threads *t*. Projecting laterally from the frame 10, are two pairs of auxiliary yarn guides 10⁵, 10⁶. The upper end of the spindle 12 carries a bevel gear 14, which meshes with a larger bevel gear 15 rotatively borne in the upper end of the frame 10 and on the axle 16 of which is 60 fixed a small pinion 17. Pivoted in the arm or extension 10', as at 18, and suitably guided in a guide member 19 provided thereon, to extend in a slanting position, is a rocking arm 20. The upper or rear end 70 of said arm is formed with or has attached to it a toothed sector 20^a adapted to be always in mesh with said pinion 17. The lower or forward part 20' of said arm is extended below the pivot 18 and bent horizontally and the end thereof has attached to it a spring 21 fixed to the extension 11' of the slide 11. Projecting vertically downward from said extension 11', is a cylindrical socket 22 in which is movably mounted a 75 plunger 23. The upper end of the plunger projects outwardly from the socket and is formed with a vertically adjustable head-piece, such as a nut 24, working on a threaded portion 23' of said plunger. The head-piece or nut 24 is adapted to bear on the flat bar 11' and thereby hold the plunger suspended within the socket 22 in normal position. The plunger is formed with a reduced threaded neck 23² projecting upwardly and 80 carrying two clamping nuts 25, 26 between which is clamped a plate or member 27 adapted to project below a set screw 29 working in the extension 20' of the arm 20. Through the medium of said member 27 and set screw 29, the vertical movement of the plunger is transmitted to the rocking arm 20. Fixed to the slide 11, is a bracket 85 28, the upper end of which projects above and is bent into the path of the extended part 20' of the rocking arm 20 and carries a set screw 30 for limiting the movement of the rocking arm 20. The lower end 23³ of the plunger 23 is substantially V-shaped, the narrow end thereof being directed down- 90

wardly and adapted to continuously bear on a jacquard card 31 extending longitudinally along the path of said plunger. This card as usual is composed of one or more sets of plates 5 31' linked together, as at 31', to an endless band and having, according to the pattern desired to be knitted, solid or slotted surfaces, over which the plunger, when moved longitudinally with the carriage, is adapted 10 to slide. When the plunger slides over a solid surface, it will be moved upwardly within its socket against the action of the spring 21 and this movement will be transmitted to the arm 20. When it reaches a 15 slot in the jacquard card, the plunger will be thrust downwardly under the action of said spring and remain in this position as long as it travels through said slot.

The jacquard band as usual is supported 20 on a grooved polygonal or prismatic shaft 32 extending longitudinally in front of the machine and rotatively and suitably supported in brackets 33 fixed to the main frame. This shaft, in a suitable manner, is 25 intermittently operated from the main shaft s of the machine through the medium of a ratchet wheel 34 and a pawl 35 cooperating therewith and suitably actuated from the main shaft s and controlled from the rack 30 shaft r in well-known manner. In order that the prismatic or polygonal shaft 32 be temporarily locked in position of rest in the range of the plunger, we provide a safety device consisting of a pawl 36 pivoted at 35 36' to a stationary part of the machine and actuated by a spring 37. This pawl is adapted to cooperate with a notched wheel 38 fixed to one end of said polygonal shaft 32 so that, when engaging one of the notches 40 of said wheel 38, it will arrest said shaft 32 in its position.

The mode of operation is as follows:—

Assuming a jacquard card for a certain 45 pattern of the fabric to be knitted mounted on the shaft 32 and assuming two threads t of different colors guided through the openings of the yarn guide 13. Normally the yarn guide 13 is so positioned relative to the needle beds that when the carriage is reciprocated and while the plunger travels over a solid surface of the jacquard card, one of the thread guides 13' will be in leading position cooperating with the needles n and forming a fabric with the thread of the particular color chosen. When, while travelling over the jacquard card, the solid surface is interrupted by a slot, the plunger entering said slot will permit the spring 21 to 50 actuate said rocking arm 20, as a result of which its toothed segment 20^a will impart half a turn to the pinion 17 in consequence of which the yarn guide 13 will be correspondingly turned to bring the other thread guide 13' into leading position to cooperate 55 with the needles n . In this position, the

yarn guide will remain until the plunger passes out from the slot and enters onto a solid part of the jacquard card. This upward movement of the plunger causes the rocking arm to swing in the opposite direction against the tension of the spring 21 through the medium of the member 27 acting against the set screw 29. 70

By the aforescribed construction, it is possible to produce knitted fabric of any 75 desired variegated pattern.

It is, of course, to be expressly understood that we do not wish to limit ourselves to the details described and shown, since various changes may be made without departing from the spirit of our invention. 80

What we claim is:—

1. The combination with a knitting machine, of a yarn carrier having a plurality of yarn guide openings selectively movable 85 to a leading position relative to a given feeding movement of said carrier and jacquard controlled means movable longitudinally of the machine and capable of moving said yarn carrier into a leading position 90 during said feeding movement of said carrier.

2. The combination with a knitting machine, of a yarn carrier having a plurality of yarn guide openings selectively movable 95 to a leading position relative to a given feeding movement of said carrier, means movable longitudinally of the machine and capable of changing the position of said carrier during the feeding movement of the 100 latter and a jacquard card adapted to automatically control said actuating means.

3. The combination with a knitting machine, of a yarn carrying element having a plurality of yarn guide openings and selectively movable to a leading position relative to a given feeding movement of said carrier, means movable longitudinally of the machine and capable of changing the position of said carrier during said feeding 110 movement of the latter, said means including a plunger, and a jacquard card on which said plunger is adapted to continuously bear and which automatically controls said actuating means through said 115 plunger.

4. The combination with a knitting machine, of a yarn carrying element having a plurality of yarn guide openings and selectively turnable to a leading position relative to a given feeding movement of said carrier, means for actuating said carrier and including a pinion and toothed sector movable longitudinally of the machine together with said carrier and capable of moving the 120 latter into a leading position during the feeding movement thereof, and jacquard controlled means for operating said sector. 125

5. The combination with a knitting machine, of a turnable yarn carrier having a 130

- plurality of yarn guide openings to be selectively brought into a leading position relative to a given feeding movement of said carrier, means for actuating said carrier movable longitudinally of the machine together with said carrier, said means including a pinion, a toothed sector and a plunger operatively connected to said sector and a jacquard card controlling the movements of said plunger. 5
6. The combination with a knitting machine, of a turnable yarn carrier having a plurality of yarn guide openings to be selectively brought into a leading position 10
- 15 relative to a given feeding movement of said carrier, means for actuating said carrier movable longitudinally of the machine together with said carrier, said means including a pinion, a toothed sector meshing therewith and means for positively transmitting rocking movement to said sector including a plunger and a jacquard card automatically controlling said plunger. 20
7. The combination with a knitting machine having two opposite needle beds, of a horizontally oscillating selectively adjustable yarn carrier fed longitudinally and centrally of said beds, means for adjusting said carrier during the feeding movement 25 of the latter and a jacquard card extending the entire length of the machine for automatically controlling the operation of said means. 30
8. The combination with a knitting machine having two opposite needle beds, of a horizontally oscillating selectively adjustable yarn carrier fed longitudinally and centrally of said beds, means for adjusting said carrier during the feeding movement 35 of the latter and a continuously fed endless jacquard card extending the entire length of the machine for automatically controlling the operation of said means. 40
9. The combination with a flat knitting machine, of a horizontally oscillating selectively adjustable yarn carrier, means for adjusting said carrier during the feeding movement of the latter and a jacquard card 45
- extending the entire length of the machine for automatically controlling the operation 50 of said means.
10. The combination with a knitting machine having opposite stationary needle beds, of a horizontally oscillating selectively adjustable yarn carrier fed longitudinally 55 of said beds, means for adjusting said carrier during the feeding movement of the latter, a jacquard card extending the entire length of the machine for automatically controlling the operation of said means and 60 means for feeding the jacquard card at each stroke of said carrier.
11. The combination with a knitting machine having opposite needle beds, of a horizontally oscillating selectively adjustable yarn carrier fed longitudinally of said beds, means for adjusting said carrier during the feeding movement of the latter, a jacquard card extending the entire length 65 of the machine for automatically controlling 70 the operation of said means, means for intermittently feeding said card at each stroke of the carrier and safety means for securing said card in operative position. 75
12. In a knitting machine having opposite needle beds, a yarn carrier having a plurality of thread guide openings and selectively adjustable to be in leading position with any one of its thread openings relative to a given feeding movement of said carrier, said carrier being formed on a rotary spindle disposed vertically and centrally between the needle beds, means for transmitting rotary motion to said spindle during the feeding movement of said carrier including a pinion, a spring actuated rocking arm having a toothed sector meshing with said pinion and a plunger for transmitting motion to said rocking arm and a jacquard card controlling the movements 80 85 of said plunger. 90

In testimony whereof we affix our signatures.
